Des. 217,410
Patented Apr. 28, 1970

217,410

TONGUE DEPRESSOR

Sidney Greatman, Canoga Park, Calif., assignor to A & E Plastik Pak Co., Inc., Industry, Calif., a corporation of California

Filed Sept. 15, 1969, Ser. No. 19,155

Term of patent 14 years

Int. Cl. D24—02

U.S. Cl. D83—12

FIG. 1 is a perspective view of a tongue depressor showing my design;

FIG. 2 is a right side view;

FIG. 3 is a bottom plan view of the tongue depressor of FIGS. 1 and 2; and

FIG. 4 is a cross section taken on line 4—4 of FIG. 1;

FIG. 5 is a cross section taken on line 5—5 of FIG. 1; and

FIG. 6 is a cross section taken on line 6—6 of FIG. 1.

I claim:

The ornamental design for a tongue depressor, as shown and described.
